(57) CLAIM

The ornamental design for a grille for a vehicle, as shown and described.

DESCRIPTION

FIG. 1 is a top, front and left side perspective view of a grille for a vehicle according to my new design;

FIG. 2 is a left, front perspective view thereof;

FIG. 3 is a top, rear and right perspective view thereof;

FIG. 4 is a right, rear perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof; and,

FIG. 11 is another right elevational view thereof shown on a vehicle.

The portions of the vehicle shown in the FIG. 11 drawing view in broken lines are all for environmental and illustrative purposes and form no part of the claimed design.
